UNITED STATES PATENT OFFICE.

HENRY KENNEL, OF NEW YORK, N. Y.

VENTILATOR FOR CARS.

No. 796,224.

Specification of Letters Patent.

Patented Aug. 1, 1905.

Application filed July 2, 1904. Serial No. 215,126.

To all whom it may concern:

Be it known that I, HENRY KENNEL, a citizen of the United States, and a resident of the city of New York, borough of Manhattan, in the county and State of New York, have invented a new and Improved Ventilator for Cars, of which the following is a full, clear, and exact description.

The purpose of the invention is to provide means for ventilating cars or other vehicles by introducing a thorough circulation of air through the clearstory of the car, thus preventing any of the occupants being subjected to draft, though the air is constantly replaced in the vehicle.

Another purpose of the invention is to provide a ventilating device adapted for attachment at the ends of the clearstory of the car which will open at the end of the clearstory facing the point from which the car travels and will close at the opposite end of the clearstory or that end which faces the point in direction of which the car is traveling, the two ventilators being independent in their operation, thus creating a suction to draw the foul air out from the body of the car.

Another purpose of the invention is to provide a means whereby when a ventilator is closed operating mediums, which are in the nature of wings acted upon by the currents of air induced by the movement of the vehicle, will at such time move to such a position as to offer the least possible resistance to the air as the vehicle moves forward.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of a part of the upper or roof portion of a car, including the clearstory and illustrating a ventilator in an open position at the rear portion of the clearstory, the roof of the clearstory being shown in section and the part of the clearstory cut away being indicated by dotted lines. Fig. 2 is an enlarged longitudinal vertical section through that portion of the car shown in Fig. 1, showing the ventilator open in positive lines and closed in dotted lines. Fig. 3 is an enlarged vertical section taken practically on the line 3-3 of Fig. 4, representing the ventilator at the rear end of the clearstory open in

positive lines and in dotted lines showing the position of the said ventilator when closed. Fig. 4 is a section taken practically on the line 4-4 of Fig. 3; and Fig. 5 is a vertical longitudinal section of an end portion of the roof of a regular railway-car, illustrating the adaptation of the improvement thereto.

A represents the roof of a car, and B the clearstory which is erected on the roof, which clearstory is provided at each end with a transverse opening 10. This opening is preferably provided at its upper portion with a longitudinal metal strip 11 flush with the outer side face of the walls of the clearstory in which the said openings 10 are made. At each end of each opening 10 in the said clearstory a bearing 12 is formed of any approved construction, and in the bearings 12 at each end of the clearstory a shaft 13 is mounted to loosely turn, which shaft extends out beyond the side faces of the clearstory, as is shown in Fig. 1.

A ventilator C is secured, preferably, to the front or outer side of each shaft 13, and each ventilator C in one position is adapted to close the opening 10 adjacent to which it is located and in another position uncovers the said opening to a greater or lesser extent. Each ventilator C, as is shown particularly in Fig. 2, comprises an outer member c and inner member c' and a socket member c², to which the said shaft 13 is secured, and when a ventilator C closes the opening 10 at the end of the clearstory the outer member c of the ventilator assumes a vertical position in engagement with the end walls of the opening 10, while the inner member c' engages with the inner face of the strip 11 at the upper edge of the opening 10; but the said parts c and c' of the ventilator may be so disposed that when the outer or lower member c is in closing position the upper or inner member c' will engage with the inner wall of the said opening 10 at the upper edge of the same.

The ventilators C are operated by the action of the air on wings D. These wings D are located at the outer ends of the shafts 13 and are connected with the inner sides of the said shafts. To that end bearings 16 are provided which are secured to the outer faces of the wings D, and the shafts 13 are free to turn in the said bearings 16. Where the shaft 13 passes through a bearing 16, the shaft is provided with a circumferential groove 14 of predetermined length, usually of a length equivalent to about one-half of the circumference of

the shaft, and these grooves 14, as is shown in Figs. 3 and 4, are provided at their ends with cushions 15, usually of an elastic material, the end portions of the grooves being longitudinally recessed to receive the said cushions. In each bearing 15 a set-screw 17 is located, and the said set-screws extend down into the grooves 14, being adapted for engagement in one position of the wings D with one or the other of the cushions 15. As the wings D are connected with one side of the shaft 13 and the ventilators C with the opposite side of the said shaft, the wings and ventilators are in parallelism. It will be understood that the wings and the ventilators may be so attached to the shafts 13 that their ends will be in longitudinal alinement.

In the operation of the ventilators when a car is in motion the forward ventilator will be closed, and the action of the wind on the wings of that ventilator-shaft will carry the said wings to such an angle rearwardly as to prevent the wings offering any resistance to the air while the car is in motion. On the other hand, the action of the air on the wings D at the rear of the car will cause the said wings to be carried upward and outward until the set-screws 17 in the bearings on the rear wings D engage with the upper cushions 15, (shown in Fig. 3,) thus causing the ventilator C at the rear to assume a corresponding angular position to the rear wings and uncover the rear opening 10 in the clearstory to a greater or lesser extent. As the door of the car is opened or while the car is in transit the air entering the car will drive out the foul air at the opening 10 at the rear of the clearstory of the car, assisted by the suction naturally created at the said rear opening 10 by the movement of the car through the atmosphere, and under such conditions it is obvious that the foul air in the car is constantly drawn out therefrom and fresh air is supplied without subjecting the passengers of the car to unpleasant drafts.

In Fig. 5 I have illustrated an adaptation of the ventilator to a railroad-car, which is usually provided with an extended hood A' at the ends of the clearstory B, and in order that the opening 10^a, which is made in the clearstory and is opened and closed by the ventilator C', may

not receive cinders and loosely-flying particles a screen 18 is carried from the ends of the car to the sides and ends of the hood A', thus covering the said hood in such manner as to prevent the entrance of cinders and yet not interfere with the passage of air. In the adaptation of the ventilating device to a railroad-car the ventilator C' when closed is made to engage at its longitudinal edges with stops 19, of any approved construction, and a regulating-rod 20 is employed for each of the ventilators C' of a car, and by the movement of the said regulating-rod upward or downward the ventilators C' may be opened more or less, as occasion may demand.

Having thus described my invention, I claim as new and desire to secure by Letters Patent—

1. In cars and like vehicles, a clearstory having an opening at each end, a ventilator mounted on a shaft at each opening, and wings having limited turning movement on the shafts for operating the said ventilators.

2. In a car or similar vehicle, a clearstory having an opening at each end, a ventilator for each opening, adapted to open and close the same, a shaft on which the ventilator is secured, and wings at the outer ends of the shafts, having limited movement on the shaft and serving in one position to operate the ventilators to move them to an open position.

3. In a car or similar vehicle, a clearstory having an opening at each end, a shaft journaled at each of the said openings, a ventilator secured to the said shaft, adapted to cover or uncover the openings in the ends of the clearstory, the said ventilator being provided with an inner and an outer member, wings located at the ends of the shafts, bearings for the shafts carried by the said wings, the said shaft within the said bearings being provided with circumferential grooves, and set-screws extending through the bearings into the said grooves of the shafts, for the purpose described.

In testimony whereof I have signed my name to this specification in the presence of two subscribing witnesses.

HENRY KENNELL.
